UNITED STATES PATENT OFFICE.

JOZEF FRANK GAKEN, OF DUNKIRK, NEW YORK.

DESIGN FOR RUBBER FOOTWEAR.

60,524.

Specification for Design.

Patented Mar. 7, 1922.

Application filed October 22, 1920. Serial No. 418,836. Term of patent 3½ years.

To all whom it may concern:

Be it known that I, JOZEF FRANK GAKEN, a citizen of Poland, and a resident of Dunkirk, in the county of Chautauqua and State of New York, have invented a new, original, and ornamental Design for Rubber Footwear, of which the following is a specification, reference being had to the accompanying drawing, forming part thereof.

The figure is a bottom plan view of rubber shoe showing my new design.

I claim—

The ornamental design for rubber footwear as shown.

JOZEF FRANK GAKEN.
